Walter Norton, Brown.

UNITED STATES PATENT OFFICE.

WALTER MORTON BROWN, OF ALBANY, NEW YORK.

DEVICE FOR HEATING WATER BY GAS.

SPECIFICATION forming part of Letters Patent No. 391,399, dated October 23, 1888.

Application filed February 20, 1888. Serial No. 264,693. (No model.)

To all whom it may concern:

Be it known that I, WALTER MORTON BROWN, a citizen of the United States, residing at Albany, in the county of Albany and State of New York, have invented a certain new and useful Improvement in Devices for Heating Water by Gas; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention consists of a water-motor, a fan, or other air-blast-producing device, a water-heating pipe or series of pipes, and forced-combustion gas-burners in combination.

The object of my invention is to supply heated water for all purposes, but especially for domestic, culinary, and bathing purposes, by first making use of the pressure of the water-supply to operate a water-motor, said water-motor being connected to and capable of operating a fan or other air-blast-producing device, the air-blast thus produced being utilized by causing it to impinge upon or enter into the flame of the gas burning at the gas-burners, thus producing a more intense heat, said gas-burners being so placed or arranged in relation to the water-heating pipe or pipes that the flame of the burning gas will impinge upon the water-heating-pipe, said water-heating pipes receiving the supply of water to be heated from the waste or discharge pipe of the water-motor. I accomplish this object by the combination of the various mechanisms illustrated in the accompanying drawings, wherein similar figures refer to similar parts throughout the several views, and wherein—

Figure 1 shows a water-motor, a fan, a forced-combustion gas-burner and a water-heating pipe combined, so arranged that the water under pressure first enters the water-motor, operates the same and the fan, and is then discharged into the water-heating pipe, where it is heated by the burning gas and discharged for use at the discharge-cock. Fig. 2 shows the same combination, but the water is first passed through the water-heating pipe, after which it passes through the water-motor,

operating the same and the fan, and is then discharged from the waste-pipe of the motor for use, the operation being precisely the exact opposite of that shown in Fig. 1. Fig. 3 shows the water-heating pipe and gas-burner in section, taken on line X X of Fig. 2, showing the arrangement of the gas and air pipe whereby the air is enabled to reach and impinge upon the gas-flame or enter therein, causing the most intense heat possible to be obtained from burning gas.

In the drawings, 2 shows the water-motor; 3, the air-blast-producing device; 4, the water-heating pipe; 5, the gas burners or perforations in the gas-pipe; 6, the air-pipe leading from the fan to the gas-burners; 7, a belt connecting the drive-wheel of the water-motor and drive-wheel of the fan; 8, the main water-supply pipe; 9, the discharge or waste pipe from the water-motor in communication with the water-heating pipe; 10, the gas-supply pipe; 12, the discharge-cock, showing the heated water being discharged therefrom in Fig. 1, but not showing the water being discharged therefrom in Fig. 2; 13, the gas-pipe forming a part or portion of the burner; and 14, the air-tips leading from the air-pipe through the gas-pipe.

The operation of this invention is as follows: Water under pressure, as from city water-work, pumps, or other devices, being allowed to flow into the water-motor causes the motor to operate at a speed proportionate to the pressure of the water in the supply-pipe, and the water-motor then operates the air-blast-producing device, creating a blast of air which flows through the air-pipe and impinges upon or enters the gas-flame, producing intense heat. The flame of the gas impinges upon the water-heating pipe and heats the water which is supplied to the water-heating pipe through the waste-pipe of the water-motor. The pressure of the water is therefore made to furnish an air-blast, with which intense heat is produced, by which the water is heated after or before it furnishes power to run the motor and fan, in accordance with which form of combination, as shown in Figs. 1 and 2, is used.

The pipe 4 is the heating-pipe, which should be of larger capacity or diameter than its inlet and outlet pipes, so that the velocity of the

flow of the water therein may be reduced as much as practical, and thus keep the water in pipe 4 for as long a period as practical, in order that it may take up all the heat possible.

5 I have shown in the drawings at Fig. 3 a form of forced combustion-gas burner, consisting of an air-pipe entered into a gas-pipe and having passage-ways for air under pressure to allow of the air entering or impinging upon 10 the gas-flame. I make no claim upon this form of burner, as it is not new, as will be seen by reference to the English patent to William Mather, No. 2,636, October 12, 1865, said patent having expired by due limitation of law, 15 and the form of burner is therefore public property; nor do I make any claim in this application upon causing a gas-flame and air-jet to converge upon a heating-pipe, a patent for such having been granted to me by the 20 United States Patent Office January 31, 1888, No. 377,015.

If it is thought desirable, a portion of the air may be taken from the air-pipe and caused to first mix with the gas before it is ignited by 25 any well-known mechanism; but I preferably burn the gas without such admixture of air, as with some gases such an admixture causes a tendency in the gas-flame to be easily extinguished.

30 I do not confine myself to the relative positions of the various parts of the combination shown in the drawings. They may be set or arranged in any position desired; but I preferably set them as shown. The drive-wheel of 35 the water-motor and the drive-wheel of the fan may be put in communication by any other means than by a belt, if desired. I preferably make use of a belt.

In order to have a perfect operation of this 40 invention the discharge of the water from the water-motor must not be held back or retarded, so as to produce a back-pressure in the motor.

I preferably make use of a fan, as shown, 45 with which to produce the air-blast; but any air-blast-producing device may be used.

Having described my invention, so that any person skilled in the art to which it appertains may make and use the same, what I

claim, and desire to obtain by Letters Patent, 50 is—

1. A water-motor having an inlet and outlet and a heating-pipe, and gas-burners arranged adjacent to said heating-pipe for heating the latter, and an air-blast-producing device, said 55 heating-pipe being attached to and in connection with the water-motor and capable of receiving the water discharged therefrom, and having a discharge-outlet for discharging the same, the air-blast-producing device being connected with the moving parts of the water-motor and capable of being operated thereby, 60 said air-blast-producing device having an outlet-pipe for the discharge of the air-blast, said outlet-pipe having jet-apertures, the said jet-apertures and the perforations in the gas-burner being correspondingly located, so that the jets of gas and air from said jet air-apertures and said gas-perforations will unite and 65 impinge upon the heating-pipe, substantially 70 as described.

2. A water-motor having an outlet and inlet and a heating-pipe, and gas-burners arranged adjacent to said heating-pipe for heating the latter, and an air-blast-producing device, said 75 heating-pipe being attached to and in connection with a water-supply and said motor and capable of discharging the water received from the water-supply into said motor, said motor having a discharge-opening for discharging 80 the same, the air-blast-producing device being connected with the moving parts of said motor and capable of being operated thereby, said air-blast-producing device having an outlet-pipe for the air-blast, said outlet-pipe having 85 jet-apertures, the said jet-apertures and the perforations in the gas-burners being correspondingly located, so that the jets of gas and air from said jet-apertures and said gas-perforations will unite and impinge upon the heating-pipe, substantially 90 as described.

In testimony whereof I affix my signature in presence of two witnesses.

WALTER MORTON BROWN.
